CLAIM

The ornamental design for a waffle with cannabis leaf shape, as shown and described.

DESCRIPTION

FIG. 1 is a top plan view of a waffle with cannabis leaf shape, according to a first embodiment of the invention.

FIG. 2 is a bottom plan view of the first embodiment.

FIG. 3 is a first side view of the first embodiment.

FIG. 4 is a second side view of the first embodiment.

FIG. 5 is a third side view of the first embodiment.

FIG. 6 is a fourth side view of the first embodiment.

FIG. 7 is a first perspective view of the first embodiment.

FIG. 8 is a second perspective view of the first embodiment.

FIG. 9 is a top plan view of a waffle with cannabis leaf shape, according to a second embodiment of the invention.

FIG. 10 is a bottom plan view of the second embodiment.

FIG. 11 is a first side view of the second embodiment.

FIG. 12 is a second side view of the second embodiment.

FIG. 13 is a third side view of the second embodiment.

FIG. 14 is a fourth side view of the second embodiment.

FIG. 15 is a first perspective view of the second embodiment.

FIG. 16 is a second perspective view of the second embodiment.

FIG. 17 is a top plan view of a waffle with cannabis leaf shape, according to a third embodiment of the invention.

FIG. 18 is a bottom plan view of the third embodiment.

FIG. 19 is a first side view of the third embodiment.

FIG. 20 is a second side view of the third embodiment.

FIG. 21 is a third side view of the third embodiment.

FIG. 22 is a fourth side view of the third embodiment.

FIG. 23 is a first perspective view of the third embodiment.

FIG. 24 is a second perspective view of the third embodiment.

FIG. 25 is a top plan view of a waffle with cannabis leaf shape, according to a fourth embodiment of the invention.

FIG. 26 is a bottom plan view of the fourth embodiment.

FIG. 27 is a first side view of the fourth embodiment.

FIG. 28 is a second side view of the fourth embodiment.

FIG. 29 is a third side view of the fourth embodiment.

FIG. 30 is a fourth side view of the fourth embodiment. FIG. 31 is a first perspective view of the fourth embodiment; and, FIG. 32 is a second perspective view of the fourth embodiment. The broken lines in FIGS. 1-32 illustrate portions of the waffle with cannabis leaf shape that form no part of the claimed design.
